(57) **CLAIM**

The ornamental design for an LED lamp, as shown and described.

DESCRIPTION

FIG. 1 is a perspective view of an LED lamp in accordance with a first embodiment showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded view thereof;

FIG. 9 is a top plan view of the LED lamp of FIG. 1 having no cover;

FIG. 10 is a perspective view of the LED lamp in accordance with a second embodiment;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is an exploded view thereof;

FIG. 18 is a top plan view of the LED lamp of FIG. 10 having no cover;

FIG. 19 is a perspective view of the LED lamp in accordance with a third embodiment;

FIG. 20 is a front elevational view thereof;

FIG. 21 is a rear elevational view thereof;

FIG. 22 is a left side elevational view thereof;

FIG. 23 is a right side elevational view thereof;

FIG. 24 is a top plan view thereof;

FIG. 25 is a bottom plan view thereof;

FIG. 26 is an exploded view thereof; and,

FIG. 27 is a top plan view of the LED lamp of FIG. 19 having no cover.

(Continued)

The broken lines in the drawings depict portions of the LED lamp that form no part of the claimed design.
